UNITED STATES PATENT OFFICE.

HENRY R. GILSON, OF BADEN, PENNSYLVANIA, ASSIGNOR TO NATIONAL METAL MOLDING COMPANY, OF PITTSBURGH, PENNSYLVANIA, A CORPORATION OF PENNSYLVANIA.

METAL-SHAPING TOOL.

1,204,970.

Specification of Letters Patent. Patented Nov. 14, 1916.

Application filed May 22, 1914. Serial No. 840,866.

To all whom it may concern:

Be it known that I, HENRY R. GILSON, residing at Baden, in the county of Beaver and State of Pennsylvania, a citizen of the 5 United States, have invented or discovered certain new and useful Improvements in Metal-Shaping Tools, of which improvements the following is a specification.

My invention relates to improvements in 10 machinery for shaping material in the form of a reversely curved strip into a helically wound tube of flexible armor for electrical conductors, etc.; it consists essentially of a forming-tool of novel shape and function 15 and of the organization of this forming-tool with other machine parts.

Figure 1 of the accompanying drawings shows the assembled machine in vertical longitudinal section; Fig. 2 shows the machine in end elevation, from the right, Fig. 20 1; Fig. 3 shows the forming-tool in which my invention centers, in side elevation; Fig. 25 4 is a front elevation of the same tool; Fig. 5 is a view in side elevation of the mandrel of the machine with the forming-tool sectionally shown in operative relative position to the mandrel—the relative positions, in other words, which the two parts sustain when organized in the machine. Fig. 6 30 is a view on much larger scale and in longitudinal section through the wall of a tube formed of a specially shaped strip, coiled in a machine of my invention. Fig. 7 is a view in transverse section of the mandrel 35 shown in Fig. 5.

Referring first to Figs. 3 and 4, 1 is the forming-tool; it consists essentially of a body in which an internal passageway is formed. This passageway is essentially 40 helical; it is formed by and between the cylindrical surface 2, and the helical surface 3, and is open at one side. In other words, it is a groove whose bottom is cylindrical, whose side-wall on one side is helical and which is open on the other side. The tool is, for assembling with the other parts, provided with an opening 4, concentric with the passageway already described, and extending through the tool from side 45 to side; and it is also, for like reasons, provided with an extended flange 5. Thus, viewed as a whole, the tool is of a general annular shape; or, considering that when assembled it surrounds a cylindrical mandrel, 50 it may properly be spoken of as a collar—

although, as will hereinafter appear, and as may be observed by referring to Fig. 5, it is unattached to such mandrel. The helical passageway already defined then is in effect a groove formed on the inner face of 60 this annulus or collar; the bottom of this groove is a cylindrical surface, it is closed on one side by the helical wall 3, and is open on the other side. It remains to be said that access is had to this groove at its 65 inner end by an opening 6 formed through the wall of the annulus, and this opening, as is best shown in Fig. 4, is preferably formed tangent to the circular contour of the passageway (when viewed in plan). As 70 the drawings show, the passageway extends through something less than one complete turn or loop of the helix to which it is shaped—less by the width of the opening 6; and opening 6 is extended into a slot open 75 at the end. Thus it appears that the forming-tool engages the strip of material on one side and along one edge and exerts its shaping stress upon those parts. The opposite side of the material is untouched by 80 the forming-tool (though it engages other parts, as will presently appear) and the opposite edge of the strip is, so far as the forming-tool is concerned, free and unconfined—except as engagement with the strip 85 at other points controls the position of the whole.

Referring now to Fig. 1, the forming-tool may be seen in its operative position, with material being drawn to it. A comparison 90 of the showing of this figure with the enlarged view of the tool itself will make plain the fact that a strip of material A supplied from a suitable source through opening 6 (the tangential opening being preferably 95 alined with the source from which the strip is fed) to the helical passageway already described, and extending beyond the passageway and being anchored at its forward end against rotation in unison with the forming die, rotation of the die (and of the still unformed portion of the strip, in unison with the die) will effect a shaping of the strip being drawn through it and produce the coiled article shown in Fig. 1 at B, advancing 100 to the left from the open end of the tool. In starting the machine, the advance end of the strip may be held by a pair of pliers. It should be remarked of the operation that the helical passageway is so shaped as to

give a "set" to a straight strip fed to the machine. The helical wall of the passageway forces the tubing forward along the mandrel as it is being formed and the cylindrical wall of the same passageway holds the edge of the strip in contact or in substantial contact with the mandrel and confines one edge of the strip while the other edge (on account of the helical shaping) is being slightly stretched. That is to say, there is a stress of distortion exerted on the advancing strip, so that if it were uncoiled it would no longer be straight but curved edgewise. When dealing with the soft metal ordinarily employed in making this flexible pipe, such a shaping of the material is not difficult, and it will readily be understood that such shaping has its advantages in affording a better and more coherent product. Not only is the advance portion of the tube in course of shaping anchored against rotation; means are preferably provided also for exerting upon it a longitudinal pull or tension; for, while the effect of the rotating die is to cause the turns of metal to crowd outward from the open end of the die, best results are obtained by spreading the successive turns of the coil and carrying the otherwise finished tube through a sizing apparatus, where minor irregularities, if any, may be "ironed out." These parts will now be described.

The "anchoring" of the partly finished tube—the holding of it against rotation—which is an essential part of the operation as a whole, is conveniently effected in part by a mandrel, about which the tube is coiled, and in part by the sizing apparatus. First regarding the mandrel. The mandrel is shown in detail in Fig. 5. It consists essentially of a long substantially cylindrical though preferably slightly tapering body 7; and since the rotation of this body is part of the operation of the machine, the end of the mandrel is formed as a screw-threaded block 8, by which it may be secured to proper supporting and rotating means. (A slight tapering of the mandrel in the direction of advance of the coiled strip facilitates such advance.) This block 8 appears in Fig. 1 and it will be understood that the long mandrel body extends to the left within the tube B to or approximately to the sizing mechanism presently to be described. The degree of the extent of the mandrel however is not a detail essential to the invention. When the parts are assembled, the forming-head 1 surrounds the mandrel; the space between the two parts is sufficient to allow the easy advance of the tube in right-line path over the mandrel rotating within it. As the operation of the machine progresses, the tube as it is formed passes out at the open end of the forming-die and advances along the body of the mandrel. The mandrel, as

has been said, rotates, and it rotates in a direction opposite to that of the forming-die. Its surface is roughened, as for example by the longitudinal fluting shown in Figs. 5 and 7. While the relative sizes are such that the tube B slips easily over the mandrel, the clearance is so slight that this rotating mandrel touching the inner surface of the tube, resists its rotation, and being provided with a series of longitudinal corrugations whose edges gripping the inner surface of the tube retards the tendency of the tube to rotate. The sizing mechanism, which as I have already said tends also to hold the finished portion of the tube from rotation, has the further function of crushing spots where the tube may perhaps be oversized and of bringing it to uniformity. It takes the form preferably of a pair of shaped rolls, 9 and 10, so arranged that the pass between them is alined with and preferably immediately adjacent the outer end of the mandrel. These rolls then receive between them immediately from the mandrel the newly coiled tube and while squeezing it, so far as need be, to standard diameter, serve also to hold the tube from turning in response to strain from the rotating head 1. The roll 10 serves at the same time as a bending roll, over the face of which, on the farther side of the roll-pass, the tube is caused to progress while under longitudinal tension. The tube thus stretched in a circular path upon roll 10 is further consolidated and "set," against the tendency to unwind.

It remains to describe the organization of the machine, to effect the correlated motions already described. Two oppositely placed standards, 11 and 12, are provided with bearing-blocks which are alined center to center. The bearing-block on standard 11 supports a shaft 13, which is stationary. In the bearing-block on standard 12 is rotatably mounted the guide-head 14, which carries the shaping-die 1. This guide-head 14 also surrounds (for purposes of rigidity) the stationary shaft 13. On the surface of shaft 13, adjacent the guide-head is mounted the spool 15, which is the source from which the strip is drawn which it is the purpose of the machine to fabricate. This spool 15 is mounted as an idler upon shaft 13 and so is free to be driven by the turning of the guide-head and unwind at the same time as fast as the strip is formed into a tube. Feed-rolls 16 and 17, and a runway 18 for the strip are also carried by the guide-head.

Rotatably mounted within the stationary shaft 13 is a rotatable shaft 19, to the end of which is screwed the mandrel by means of the block 8 upon the end of it. Shaft 19 projects rearwardly beyond the hollow shaft in which it turns, and it is held from longitudinal displacement by a retainer 20, car-

ried on the standard and entering a grooved collar made integral with the shaft. By loosening retainer 20 the shaft 13 and all that it contains may be drawn endwise through the bearing block in standard 11, and thus the drum 15 may be removed and replaced.

The guide-head 14 and the shaft 19 (the one carrying the shaping-die, the other the mandrel) may conveniently be rotated in opposite directions and at desired relative speeds from a common power-shaft 21, the one by the sprocket-drive 22, the other by the sprocket-drive 23 and the gear-wheel 15 drive 24.

The sizing rolls 9 and 10 may be geared together, as shown, and driven from the shaft 21 also by the worm 25 and such interconnected gearing as that shown. The roll 26, coöperates with roll 10 to shape the tube as it passes from between rolls 9 and 10 and subject it to the bending, pulling and setting action already referred to.

The shape of the strip in cross-section for the coiling of which this machine is well designed is indicated in Fig. 6, where two interlocking turns of material are shown in section. In the shaping operation it is the portion of the strip which forms the wall of smaller diameter that the shaping-die immediately engages. It will be observed in this figure that a packing C, which may be

a strand of rolled paper, is interposed in the overlap of adjacent turns. Referring to Fig. 2, a reel 27 is shown carried by the rotating guide-head; this reel carries a supply of paper filler which is fed into place as the strip enters the shaping-die, as indicated in Fig. 1.

I claim as my invention:

In a machine for forming flexible interlocking metallic armor from a single reversely curved strip of metal, the combination of a mandrel, a collar surrounding said mandrel and rotatable with respect thereto, said collar having on its inner face a groove whose bottom is a cylindrical surface, whose wall at one side is a helical surface, and which is open at its opposite side, said groove being accessible by an opening extending through the collar, and the width of said groove measured from its helical to its open side being substantially less than the width of the strip of which the armor is formed, whereby said collar engages and elongates the rear edge of said strip to bring it to armor-forming shape.

In testimony whereof I have hereunto set my hand.

HENRY R. GILSON.
